REED MOUNTING WITH METAL TONGUES
FOR MUSICAL INSTRUMENTS

René Seybold, Strasbourg-Meinau, France

Application September 10, 1947, Serial No. 773,261
In Germany November 20, 1942Section 1, Public Law 690, August 8, 1946
Patent expires November 20, 1962

8 Claims. (Cl. 84—363)

1

In the harmonium, as well as in accordions or similar instruments, the tone producing elements are permanently tuned metal reeds which, without hindrance in their own periodicity, can vibrate within the slot of a reed-mounting. These reed-mountings together with the necessary slots have hitherto been produced through the pressure casting process, or the slots destined to receive the vibrating reeds were stamped from a whole sheet of metal by means of cutting tools. With these processes great stress was laid on a minimum of air space between reed and sidewalls of the slot or its cutting edges, respectively, since the wind consumption becomes less, the lesser the air space is.

With reed-mountings of good quality, the sidewalls of the slots would then be retouched by hand or calibrated by machine in such a manner that the sidewalls of the slot, beginning at the cutting edge and for a distance of approximately 1.5 mm. would lie at right angles to the outer edge, or the surface of the plate, respectively, and from there flared slightly conically to the back-side of the plate.

In accordions, stamped reed-mountings are frequently used on which a reed is mounted on each side of the frame. Such reed-mountings have the disadvantage that the slots are slightly rounded on the side on which the cutting tool enters the plate so that only the other side, on which the tool leaves the plate, is provided with sharp edges along the slots. For acoustic reasons, however, there should be sharp edges on both sides for the plate and in order to achieve this, the plates are usually milled again. Through this process, however, the dimensions of the slots are frequently altered so that the reeds no longer fit exactly.

The object of the invention is a reed-mounting with metal reeds for musical instruments which differs from the accustomed processes in that it consists of at least two superimposed and mutually joined plate-like parts with slots of different dimensions.

On the accompanying drawings one reed-mounted for two reeds is represented as an exemplary presentation of the object of the present invention. Thus:

Fig. 1 shows a perpendicular view on a plate-like part,

Fig. 2 shows a cut along line II—II in Fig. 1,

Fig. 3 shows a perpendicular view on another plate-like part,

Fig. 4 shows a cut along line IV—IV in Fig. 3,

Fig. 5 shows a longitudinal cut through a reed-

2

mounting composed of the two plate-like parts shown in Figs. 1 and 3 and one reed,

Fig. 6 shows a cut along line VI—VI in Fig. 5.

The reed-mounting depicted here is composed of two plate-like parts. One of these two parts consists of an upper frame-plate 1 showing a longer slot 2 and a shorter slot 3, the two slots lying side by side and oriented in the longitudinal axis of the plate. The lengths of these slots are 10 designated in Figs. 2 and 4 with A and B, respectively, and their width, in Fig. 6 with C and D, respectively. Slots 2 and 3 could both also have identical lengths, as shown by the dotted lines in Figs. 1 and 3. In the frame-plate 1 drill holes 4, 5, 6 and 7 are provided for rivets. The one narrow edge 8 of frame-plate 1 is turned up at right angles.

The second plate-like part of the reed-mounting consists of a lower frame-plate 9 which is 20 shaped exactly like the upper frame-plate 1. The longer slot is designated with the number 11, the shorter with 10 and the rivet holes with 12, 13, 14 and 15. The narrow edge 16 is turned down.

25 In order to form a reed-frame the two frame-plates 1 and 9 are superimposed on each other in such a manner that a T-shaped longitudinal cut results and that rivet holes 5 and 13, 4 and 12, 7 and 15 as well as 6 and 14 lie on top of each other.

The reed-mountings of accordions, for example, have usually a thickness of approximately 3 mm. For the construction of such a reed-frame, therefore, two frame-plates of 35 1.5 mm. thickness each are used so that the resulting reed-mounting possesses the customary thickness. The slots of these relatively thin plates can, as experience shows, be machined accurately and neatly so that no subsequent milling 40 is required. The dimensions of the slots can be kept within such accurate tolerances that, on the cutting edge, they correspond accurately to the dimensions of reed 17 (Fig. 5) from base to tongue end and that thus the air space between 45 reed and cutting edge can be reduced to a minimum.

As can be seen from Fig. 6, the shorter slots 3 and 10 of the two frame-plates are wider than the longer slots 2 and 11. The ends of the shorter slots 3 and 10, lying near the tongue end of the reed, do not extend quite as far as the longer slots 2 and 11, as shown in Fig. 5. Hence, there is somewhat more play between the walls 55 of the shorter slots 3 and 10 and reed 17 than

between the reed and the walls of the longer slots 2 and 11.

The two frame-plates 1 and 9, as well as the reed 17 are joined together by means of a rivet 18 (Fig. 5). The shaft of the rivet has different diameters (i. e., partly countersunk head) so that drill holes 4 and 12 are provided with different but suitable diameters, concentrically superimposed. The second reed—not shown in the drawing, but—belonging to the superimposed slits 3 and 11 is fastened by means of a rivet set in drill holes 5 and 13. Two rivets 19 through drill holes 7 and 15 and 6 and 14, respectively, fasten together the frame-plates 1 and 9 near the tongue end of the reed. As can be seen from the arrangement and articulation of the superimposed slots 3 and 11, as well as 2 and 10, the second, and not shown, reed is, in contrast to reed 17, affixed on the lower frame-plate 9 and lies opposite the longer slot 11. The detailed exemplary drawing (shown here) is therefore intended for two streams of air coming from opposite directions.

By means of the different dimensions of the shaft (i. e., the partly countersunk head) of rivet 18 a firm juncture of the frame-plates, as well as a firm seat of the reed, is achieved—a fact of great importance for the vibrating action and for the maintenance of correct pitch. The flanged ends 8 and 16 serve the purpose of making airtight the open sides of the compartments of the soundboard into which the reed-frames are fitted by means of grooves.

The reed-frames could also be constructed of more than two superimposed and mutually joined frame-plates. The frame-plates could also be provided with slots in such a fashion that the resulting reed-frames possess more than two reeds.

I claim:

1. In a music instrument, the combination of a reed-plate comprising two elementary identical elongated plates provided with two parallel longitudinal slots of different lengths, means for superposing said plates in joined relationship through corresponding faces and a reed secured to the free face of each elementary plate and registering with the longer slot therein.

2. In a music instrument, the combination of a reed-plate comprising two elementary identical elongated plates provided with two parallel longitudinal slots of different lengths, the cooperating ends of the two slots being very near alignment with one another with a slight relative longitudinal shifting, means for superposing the plates in joined relationship through corresponding faces and a reed secured to the free face of each elementary plate near the opposite end of the longer slot of the corresponding plate for registering with the said slot.

3. In a music instrument, the combination of a reed-plate comprising two elementary identical elongated plates provided with two parallel longitudinal slots of different lengths, the shorter slot being slightly wider than the longer slot, means for superposing said plates in joined relationship through corresponding faces and a reed secured to the free face of each elementary plate and registering with the longer slot therein.

4. In a music instrument, the combination of a reed-plate comprising two elementary identical elongated plates provided with two parallel longitudinal slots of different lengths, the cooperating ends of the two slots being very near alignment with one another with a slight relative longitudinal shifting, a reed secured to the free face of each elementary plate and registering with the longer slot therein and common rivets rigidly securing together each reed with both elementary plates.

5. In a music instrument, the combination of a reed-plate comprising two elementary identical elongated plates provided with two parallel longitudinal slots of different lengths and superposed through corresponding faces, a reed secured to the free face of each elementary plate and registering with the longer slot therein, and common rivets rigidly securing together each reed with both elementary plates.

6. In a music instrument, the combination of a reed-plate comprising two elementary identical elongated plates provided with two parallel longitudinal slots of different lengths, corresponding ends of which slots being in substantial alignment, means for superposing said plates in joined relationship through corresponding faces and a reed secured to the free face of each elementary plate and registering with the longer slot therein.

7. In a music instrument, the combination of a reed-plate comprising two elementary identical elongated plates provided with two parallel longitudinal slots of different lengths and including a depending flange at one of their small ends, means for superposing said plates in joined relationship through corresponding faces with the flanges of each plate directed away from the other plate and a reed secured to the free face of each elementary plate and registering with the longer slot therein.

8. In a music instrument, the combination of a reed-plate comprising two elementary identical elongated plates each provided with two parallel longitudinal slots of different lengths said plates being disposed one above the other face to face, a reed secured to the free face of one of the elementary plate and registering with the longer slot therein and rivets securing the two plates together, the diameter of said rivets being stepped in register with the two elementary plates through which the rivets pass.
